UNITED STATES PATENT OFFICE.

HARRY SWINGLEHURST, OF BOSTON, MASSACHUSETTS, ASSIGNEE TO SCOTT & WILLIAMS, INC., OF PHILADELPHIA, PENNSYLVANIA, A CORPORATION OF NEW JERSEY.

WEB-HOLDING MECHANISM FOR CIRCULAR-KNITTING MACHINES.

1,147,987.

Specification of Letters Patent.

Patented July 27, 1915.

Application filed October 5, 1911. Serial No. 653,002.

To all whom it may concern:

Be it known that I, HARRY SWINGLEHURST, a citizen of the United States, and a resident of Boston, in the county of Suffolk and State of Massachusetts, have invented an Improvement in Web-Holding Mechanism for Circular-Knitting Machines, of which the following description, in connection with the accompanying drawings, is a specification, like characters on the drawings representing like parts.

This invention relates to web-holding, or, as sometimes named, sinker mechanism for circular knitting machines and more particularly to means for operating independently movable web-holders or sinkers in connection with independently movable knitting needles.

In order that the principle of my invention may be better understood, I have disclosed a single embodiment thereof in the accompanying drawings, in which—

Figure 1 is a side elevation of a circular knitting machine embodying my invention; Fig. 2 is a detail in transverse section on the line 2—2 of Fig. 1; Fig. 3 is a plan view of the structure shown in Fig. 1; Fig. 4 is a front elevation of the upper portion of a knitting machine embodying my new devices; Fig. 5 is a plan view of the sinker or web-holder cam ring; and Fig. 6 is a transverse vertical section thereof.

I have chosen to illustrate my invention as applied to a circular knitting machine of the general type disclosed in the patent to George D. Mayo, No. 726,178, dated April 21, 1903, but in the particular machine illustrated the needle cylinder is rotatable and the cam ring is relatively stationary, although the reverse construction, as in said patent, may be employed so far as certain features of the invention are concerned.

The knitting machine to which I have represented my invention as applied, is provided with a single stitch cam, it being understood that if the machine be a multi-feed machine, it will be provided with a single or other stitch cam for each yarn feed.

So far as certain features of the invention are concerned, the character of the knitting cam mechanism may be widely varied within the scope thereof.

A knitting machine having a rotary nee-

dle cylinder and a stationary cam ring is preferable to one having the reverse arrangement of such parts, first, because higher speeds are attained, inasmuch as less mass is in motion during the knitting operation, and secondly, because in multiple feed machines or in machines where yarn changers or splicers are employed and a number of bobbins are used, these bobbins can occupy a stationary position instead of revolving about the axis of the machine as they must, when the needle cylinder is stationary and the cam ring is caused to rotate or reciprocate thereabout.

In knitting machines of the single knitting cam type, it is necessary, in order to keep the yarn guide always in the lead of the stitch cam, that a certain relative position be maintained between said guide and cam during the knitting operation. Therefore, when the machine is reciprocated as in narrowing and widening, the stitch cam must change its relation to the yarn feed on each change in the direction of movement of the machine, so that said yarn feed may always be in the lead of the stitch cam. When, as in the machine of the said Mayo Patent No. 726,178, the cam ring is the moving element, this is readily effected by providing for lost motion between the driving gear ring and the cam ring, so that on each change in the direction of motion of the driving gear ring, the cam ring will remain stationary until the yarn guide has secured the proper lead with respect to the stitch cam. When, however, the machine has a rotating or reciprocating needle cylinder and the cam ring is normally stationary, this method of operation cannot be utilized.

In my co-pending application Serial No. 628,055, filed May 18, 1911, (Letters Patent No. 1,087,698, February 17, 1914) I have fully disclosed and claimed means whereby in the rotatable needle cylinder type of knitting machine, movement is imparted to the cam ring on each change in the direction of motion of the needle cylinder thereby to shift the stitch cam with relation to the yarn guide, so as to preserve the proper lead of the yarn guide with respect to the stitch cam during all stages of the knitting operation.

Referring more particularly to the drawings, the needle cylinder is represented at 1,

the said cylinder being supported upon the bed plate 2 and having a flange by which rotary motion is imparted thereto by a beveled gear upon the main drive shaft of the machine. Surrounding the needle cylinder is a cam ring 3 preferably mounted on a fixed ring on the bed plate 2 so as to be free to turn thereon.

By preference, the cam ring is positively moved to the desired extent on each change in the direction of movement of the needle cylinder. For this purpose, I have herein represented at 144 the shaft carrying the quadrant whereby to and fro movements are imparted to the driving shaft of the machine, preferably by means of a connecting rod 142 and a rotating drive wheel, and at 92 a shaft controlling the operation of the reinforcing mechanism of the yarn supply of the machine, and to which a rocking motion about its vertical axis is imparted whenever the machine changes from rotary to reciprocal knitting, or vice versa, said parts having similar numbers to those applied to the corresponding parts as shown in the Mayo patent above referred to and operating in the same manner as the corresponding parts in the machine of said patent.

Upon the shaft 144 are mounted, so as to be free to swing, two levers 5, 6, the lever 5 being connected by a link to the said connecting rod, whereby the latter, which is constantly acting to impart rocking movement to the toothed quadrant of the machine, also imparts constant rocking movement to said lever 5. The hub of the lever 5 is slotted as indicated at 7 for the reception of a key 8 carried by a pin 9 free to slide longitudinally in a bored out portion of the shaft 144, the latter also receiving a coiled spring 10 acting upon a shoulder on said pin to project the same.

The lever 6 is provided with a bushing free to turn upon the hub of the lever 5 and having slots 11 for the reception of said key 8 when the latter has been moved into line therewith and then inwardly, said key being free from said slots when moved outward as shown in Fig. 2. The position of said key therefore determines whether the lever 6 is clutched to the lever 5 or is free from operative connection therewith. The end portion of the shaft 144 may be slotted, the slots in said shaft and the bushing of the lever 6 being of such width as to permit free play of the key 8 therein. A washer secured to the end of the shaft 144 serves to retain the parts in proper position upon the latter.

The shaft 92 is provided at a point in line with the pin 9 with a projecting pin 13. When the machine is knitting round and round, said shaft 92 occupies the position shown in Fig. 2, said pin 13 being at right angles to the pin 9 and free from contact therewith, so as to permit the spring 10 to

project the pin 9 to its full extent. When, however, the parts are operated so as to change the machine from rotary to reciprocal movement, rocking movement is imparted to the shaft 92 and the pin 13 thereof is moved so as to strike the end of the pin 9 and move it inwardly or toward the left, viewing Fig. 2, this action taking place at a time when the key 8 is in line with the slots in the hub of the lever 6, so as to cause said key to enter said slots, thereby clutching the lever 6 to the lever 5 and causing said levers to oscillate together. The outer end of the lever 6 is provided with a cam 14, with which engages an anti-friction roller or projection 15 upon an arm 16 secured to an upright shaft 17 journaled in suitable brackets 18 fixedly secured to the framing of the machine. Fast upon the upper end of the shaft 17 is an arm 19 connected by link 20 to the flange of the cam ring 3, as most clearly shown in Fig. 3.

When the machine is knitting round and round, the parts occupy such relation to one another that the stitch cam of the cam ring 3 occupies the proper position in the rear of the yarn guide. As soon as the machine changes from rotary to reciprocal knitting, motion of shaft 17 causes the cam ring to move with the needle cylinder until the stitch cam occupies a position at the other side of the yarn guide, the needles then continuing to move past the cam, and when the driving movement of the machine is again changed for the production of the second course of reciprocal knitting or for changing back to round and round knitting, a reverse movement of the stitch cam is effected, thereby positioning the same in proper relation to the thread guide.

Any other suitable means may be provided positively to move the cam ring with respect to the yarn guide, so as to permit the latter to have the proper lead, and if desired I may provide means such as shown in my application above referred to, to lock the cam ring in either position.

Within the scope of my invention, I may shift the cam ring at the indicated intervals otherwise than in a positive manner, and if desired as indicated in said application.

The machine herein disclosed is provided with suitable picker mechanism to act upon individual needles in narrowing and widening, said mechanism being of any suitable type and such for example as disclosed in my Letters-Patent No. 1,057,782, dated April 1, 1913.

In order to elevate the instep needles prior to the commencement of narrowing and widening, and also when desired to elevate all the needles to permit removal of the needle cylinder or for other purpose, I may provide a switch cam 21 having means operatively connected to a moving part of the

machine to move said cam into elevated or depressed position with respect to the needles. Said switch cam is so constructed and mounted as to be capable of manual movement from its elevated to its depressed position. I do not herein claim the switch-cam or its operating means.

The needle cylinder is provided with a sinker ring to receive the sinkers. The ring and sinkers and the cam mechanism therefor may be generally similar to those shown in the said Mayo Patent, No. 726,178. I, however, provide certain adjustments to control the throw of the sinkers, and particularly to prevent over movement of the sinkers radially inward.

Referring to Figs. 5 and 6, I have therein represented a sinker cam ring 48 having thereon a draw-out cam 49 and two push-in cams 50 pivoted at 51 upon the sinker ring so that they may be adjusted as desired. To effect such adjustment I provide said cams with set screws 52 taking into slots 53 in the cam ring, thereby permitting adjustment of said push cams in and out. The draw-out cam 49 is stationary and, inasmuch as adjustment of the push-in cams 50 may result in over movement of the sinkers and also to control at all times the movement of the sinkers, I provide adjustable cams 54 pivoted at 55 and provided with set screws 56 taking into slots in the sinker cam ring to secure them in adjustable position. As shown in Fig. 6, the ends of the stationary draw-out cam 49 are of reduced thickness as indicated at 57, to receive said adjustable cams 54. The outer edges of the adjustable cams 54 form substantial continuations of the draw-out cam 49 in either direction of rotation.

Consequent upon the change from the construction specifically illustrated in said Mayo patent, in which the cam ring and cams were the actuated elements, the sinker cam ring, in order that the butts of the web-holding sinkers now moving with the needle cylinder may be actuated, is in my improved device held relatively stationary with respect to the now stationary knitting wave. Means for this purpose, as in said patent, may comprise lugs 117 on said sinker cam ring, and adjustable stop screws 116 to take on either side of a post 45 erected on the support 4 for this cam-ring which post may be as shown in said patent, one of the supports for the latch ring and yarn feed guide.

To coöperate with my new device for positively adjusting the position of the needle cam-ring with respect to the remainder of the relatively stationary devices, comprising the yarn-guide and the sinker-cams, I provide the sinker cam ring 48 with draw-in cams 50 at a proper distance apart, as shown in Fig. 5 to coöperate respectively with the cams in the needle cam-ring 3 when

said cam ring is in either extreme of its movement during reciprocal knitting. As well understood in the art, the cams 50 push the web-holders or sinkers in to prevent the forming fabric from rising by friction with needles rising from the retracted loop-drawing position reached when the apex of the stitch cam is in contact with their operating butts. The rising phase of the knitting wave is shifted at each reciprocal stroke by the device for moving the ring 3, to bring it under the sinkers in contact with the respective sinker-cam 50.

Having thus described one illustrative embodiment of my invention, I desire it to be understood that although specific terms are employed, they are used in a generic and descriptive sense and not for purposes of limitation, the scope of the invention being set forth in the following claims.

Claims:

1. Sinker cam mechanism for circular knitting machines comprising a draw-out cam, two pivoted adjustable push-in cams at opposite sides thereof, and a pair of adjustable cams, the outer edges thereof forming substantial continuations of the guiding edge of said draw-out cam. 90

2. Sinker cam mechanism for circular knitting machines comprising a draw-out cam, adjustable push-in cams at opposite sides thereof, and a pivoted adjustable cam at each end of said draw-out cam. 95

3. Sinker cam mechanism for circular knitting machines comprising a stationary draw-out cam having ends of reduced thickness, adjustable push-in cam mechanism co-acting with both said draw-out cams, and adjustable cams superposed upon the reduced ends of said draw-out cam. 100 105

4. Sinker cam mechanism for circular knitting machines comprising a stationary draw-out cam, adjustable push-in cam mechanism co-acting with both ends of said draw-out cam and adjustable cams at the ends of and forming substantial continuations of said draw-out cam and between which and said adjustable push-in cam mechanism the sinkers are guided. 110

5. Sinker cam mechanism for circular knitting machines comprising a draw-out cam and an adjustable push-in cam co-acting therewith and between which and said draw-out cam the sinkers are guided, and an adjustable cam at the end of and forming a substantial continuation of said draw-out cam. 115 120

6. In a knitting machine a needle cylinder, means to rotate and oscillate said cylinder, a cam ring and a knitting cam, means to oscillate the cam ring to adjust the position of the knitting cam and means to hold said cam ring fixed in its adjusted position, web-holding sinkers associated with said cylinder, and a relatively fixed cam ring for 125 130 135

actuating said sinkers having cams adapted to coöperate with the knitting cam in either of its adjusted positions.

7. In a knitting machine a needle cylinder, means to rotate and to oscillate said cylinder, a cam ring and a knitting cam, means to oscillate the cam ring to adjust the position of the knitting cam, and means to hold said cam ring fixed in its adjusted position, web-holding sinkers associated with said cylinder, and a relatively fixed cam ring for actuating said sinkers having cams including independently adjustable draw-out cams adapted to coöperate with the knitting cam in either of its adjusted positions.

8. In a knitting machine, a needle cylinder, means to rotate and to oscillate said cylinder, a cam ring and a knitting cam

thereon, means to oscillate the cam ring to 20 adjust the position of the knitting cam, and means to hold said cam ring fixed in its adjusted position, web-holding sinkers associated with said cylinder, a sinker cam-ring for actuating said sinkers and means to hold said sinker cam ring relatively fixed 25 during movement of said needle cylinder, said sinker cam ring having thereon cams respectively adapted to coöperate with the knitting cam when at each extreme of its 30 oscillation.

In testimony whereof, I have signed my name to this specification, in the presence of two subscribing witnesses.

HARRY SWINGLEHURST.
